LAMP

Hubert M. Greist and George J. La Vigne, New Haven, Conn., assignors to Greist Manufacturing Company, New Haven, Conn.

Application February 9, 1931. Serial No. 514,398

9 Claims. (Cl. 240—73)

This invention relates to lamps, and more particularly to a portable lamp provided with a shade detachably secured to the lamp standard.

In devices of this class, and particularly in connection with portable electric lamps, the shades are often constructed of glass, while the lamp standard is constructed of metal. It is, therefore, necessary to provide some way of securing the glass shade to the metal standard, and, as the shade is subject to breakage, it is desirable that the shade be detachably secured so that, in case it becomes broken or cracked, it may be readily removed and replaced with a new one.

One object of the present invention, therefore, is the provision of new and improved means for securing a glass shade upon the metal lamp arm.

Another object of the invention is the provision of means for securing a shade of glass or the like upon a lamp so that the shade may be readily detached, but when secured in place will be rigidly held against accidental displacement.

A still further object of the invention is the provision of means for securing the glass shade upon a lamp which will be both efficient and economical to manufacture and by means of which the shade will be held securely in place without excessive strain upon any of the parts and particularly the glass shade which might result in the breakage thereof.

To these and other ends, the invention consists in the novel features and combinations of parts to be hereinafter described and claimed.

In the accompanying drawing:

Fig. 1 is a side elevational view of a portable electric lamp embodying our improvements;

Fig. 2 is a cross-sectional view of the shade and holding means therefor taken on line 2—2 of Fig. 3;

Fig. 3 is an elevational view of the shade-holding means from the interior of the shade;

Fig. 4 is a sectional view on line 4—4 of Fig. 3;

Fig. 5 is a detail elevational view of the supporting plate, and

Fig. 6 is a detail elevational view of the clamping means secured to the shade.

To illustrate a preferred embodiment of our invention, we have shown a lamp having a base 10, a standard 11 and an arm 12 pivoted to the standard at 13 so that the shade may be adjusted at various angles relatively to the standard. At the end of the arm 12 is secured a supporting plate 14 shown more especially in Fig. 5, this plate being secured to the arm by the rivets 15 passing through the plate and

through the laterally turned ends 16 on the arm sections, and also by means of tongues 17 on the ends of the arm sections being passed through the openings in the plate and turned laterally to clamp the parts together. To the 60 plate 14 is secured a hollow boss or sleeve member 18 having an external threaded portion 19 upon which is received a knurled nut 20. The sleeve 18 is, as shown, also provided with a shoulder portion 21 adjacent the plate. 65

As shown in Fig. 5, the plate 14 is substantially semi-circular or segmental in shape and is provided along its lower edge with a horizontally extending base flange 22 to serve as a bottom rest or support for the shade, as will 70 be hereinafter explained. At one end this flange is provided with an integral arm extending therefrom to support the lamp socket. This arm comprises an upwardly extending portion 23, a horizontal portion 24 which extends longitudinally of the shade, and a horizontally and transversely extending portion 25 which extends outwardly in a direction away from the plate. 75

The portion 25 of the arm has an opening 25^a formed therein and the metal of the arm about 80 this opening is displaced outwardly to provide a flange 26 surrounding the opening. It will be understood that the arm is of flat sheet material and the opening preferably will be provided therein by the striking out of the metal to 85 provide the flange. This flange is inserted in an opening in the base of the socket 27 and crimped or expanded outwardly over the edge of the opening and over a washer 27^a disposed within the base of the socket to secure the socket 90 to the arm. This method of construction also provides for the cord entering the socket through the opening 25^a of the arm.

The shade 28, as shown in the drawing, is provided adjacent the central portion of its rear wall with a segmental opening 29 about which is a rearwardly extending flange 30. A clamp member, as will be presently described, is secured within this segmental opening, and clamped upon the edge of the shade about this 100 opening. This clamp member is permanently secured to the shade and is employed to secure the shade in place so that any pressure exerted by the securing or clamping devices will be borne by this member and not by the glass portion 105 of the shade.

This clamp member comprises front and back portions 31 and 32 of segmental shape, the back portion 32 being provided with a flange 33 to 110 overlie the flange 30 upon the shade, while the

front portion 31 being provided with an extended end 34 bears against the inner face of the shade about the opening 29. The front and back portions of the clamp member are integrally joined at their bases by a horizontal portion 35 so that, as will be obvious, the clamp member is substantially U-shaped in cross-section. These two members are secured together by means of the rivets 36 so that they bind tightly upon the edge of the shade about the arcuate opening 29.

A spring 37 is provided between the front and back portions of the clamp member and has its ends secured about the rivets 36. This spring is, as shown in Fig. 5, provided with an intermediate loop or bight portion 38 below which is a contracted portion 39. The loop portion of the spring is provided at the central portion thereof and lies within openings 40 provided within the front and rear clamp portions 31 and 32. A detail portion of the shade with the clamp member thereon is shown in Fig. 6, and it will be apparent that the openings 40 constitute recesses or notches cut through the lower base portion 35 of the clamp member so that this member may be passed downwardly over the hollow threaded sleeve 18, the width of the openings 40 being slightly larger than the diameter of the shoulder portion 21 of this sleeve. The contracted portion 39 of the spring will preferably be slightly smaller than the hollow sleeve 18 so that it will be necessary to distort or open the spring slightly to force the shade downwardly upon the sleeve, which latter will, when the bight portion 38 of the spring is seated thereon, be gripped by the spring so that the shade will be resiliently held in place.

When the parts are assembled, the shade with the clamping member thereon will be moved downwardly between the socket-supporting member 24 and the plate 14 until the hollow sleeve 18 passes within the contracted portion of the spring, and the base 35 of the clamp member rests upon the supporting flange 22 of the plate 14. It will be apparent that this flange will support the shade from below and this, together with the binding action of the portion 38 of the spring, will prevent any tendency of the shade to tilt or to become accidentally displaced when the nut 20 is screwed upon the threads 19.

It will be observed that this nut is provided with a smaller body portion 42 which enters the opening 40 in the front portion 31 of the clamp member, and a head provided with a shoulder 43 which abuts the front plate so as to bind the clamp member tightly against the plate 14. The cord 44 may be passed through the arm 12, through the hollow sleeve 18, and through an opening 45 in the arm 25 to enter the base of the socket 27.

It will be apparent that the shade will be tightly clamped in position, and that any strain upon the parts will be borne by the clamp portions 31 and 32 and at the same time by unscrewing the nut 20, the shade may be readily removed if it is necessary to replace it. It will also be apparent that the shade is secured against any likelihood of its being accidentally displaced or tilted while in use.

While we have shown and described a preferred embodiment of our invention, it will be understood that it is not to be limited to all of the details shown, but is capable of modification and variation within the spirit of the in-

vention and within the scope of the appended claims.

What we claim is:

1. A lamp having a shade-supporting arm, said arm being provided with a plate and a post projecting from the plate, a shade supported by the arm, means secured to said shade having spring arms to embrace and engage the post, and means to clamp the shade against the plate. 80

2. A lamp having a shade-supporting arm, said arm being provided with a plate and a post projecting from the plate, a shade supported by the arm, means secured to said shade having spring arms to embrace and engage the post, means to clamp the shade against the plate, and said plate being provided with a horizontally extending flange to support the shade from below. 85

3. A lamp having a shade-supporting arm, said arm being provided with a plate and a post projecting from the plate, a shade supported by the arm, said shade being provided with means having spring arms to embrace and engage the post, means to clamp the shade against the plate, said plate being provided with a horizontally extending flange to support the shade from below, and said shade being provided with an opening through which said post projects. 90

4. A lamp having a shade-supporting arm, said arm carrying a plate having a horizontally extending flange thereon, a shade having its lower edge resting on said flange, said shade being provided with an opening through its lower edge, a clamp member secured to the shade within said opening, means to bind said clamp member against said plate to secure the shade on the arm, said plate being provided with a post received in the opening in the clamp member, and resilient means within the opening to embrace the post and secure the shade thereon. 100

5. A lamp having a pivoted shade-holding arm, said arm being provided with a plate and a post projecting from said plate, a shade supported by the arm, said shade being provided with an opening through its lower edge, a clamp member of resilient material permanently secured to the shade within said opening, and said clamp member being provided with an opening to receive the post, and means upon the post to bind said clamp member against the plate to secure the shade upon the arm. 110

6. A lamp having a pivoted shade-holding arm, said arm being provided with a plate and a post projecting from said plate, a shade supported by the arm, said shade being provided with an opening through its lower edge, a clamp member of resilient material secured to the shade within said opening, and said clamp member being provided with an opening to receive the post, means upon the post to bind said clamp member against the plate to secure the shade upon the arm, said clamp member comprising a piece of resilient material doubled upon itself to embrace the edges of the opening in the shade, and spring means between the sides of said member to yieldingly engage the post. 120

7. A lamp having a pivoted shade-supporting arm, a plate carried by said arm having a horizontally extending flange thereon, a shade having its lower edge portion resting on said flange, a clamp member secured to the shade and provided with an opening therein, a post projecting from the plate through said opening, a nut threaded on said post to bind the clamp member against the plate, and resilient means car- 130

150

ried by the clamp member in said opening adapted to embrace said post.

8. A lamp having a shade-supporting arm, said arm being provided with a plate and a post projecting from the plate, a shade supported by said arm, said shade being provided with an opening extending through its edge where it may be mounted upon the post laterally thereof, and resilient means secured to the shade within said opening and designed to yieldingly grip said post, and means mounted upon the post to secure the shade in place.

9. A lamp having a shade-supporting arm,

said arm being provided with a plate and a post projecting from the plate, a shade supported by the arm, said shade having an opening extending through its bottom edge whereby it may be positioned over the arm laterally thereof, and resilient means secured to the shade within said opening to grip the said post, said resilient means being adapted to spring apart to receive the post therebetween, and means to clamp the shade upon the post.
